UNITED STATES PATENT OFFICE.

WILHELM ALBERT STELLMACHER, OF ARBON, SWITZERLAND.

EMBROIDERING-MACHINE.

1,160,338.

Specification of Letters Patent. Patented Nov. 16, 1915.

Application filed October 9, 1912. Serial No. 724,808.

To all whom it may concern:

Be it known that I, WILHELM ALBERT STELLMACHER, a citizen of the Republic of Switzerland, and residing at Arbon, Switzerland, have invented certain new and useful Improvements in Embroidering-Machines, of which the following is a specification.

The present invention has reference to 10 certain new and useful improvements in embroidery machines, and relates more specifically to improved means for suspending the work-frame, on which the ground-work is stretched; and the particular object 15 of the invention is to so suspend this frame that an easy, even displacement of the frame is assured in all positions and the operating height and width of the machine is not encroached upon in any way.

20 The nature of my invention will best be understood when described in connection with the accompanying drawings, in which—

Figure 1 represents a side elevation of a 25 preferred form of construction; Fig. 2 is a front elevation thereof; Fig. 3 shows a front elevation of a constructional modification; Fig. 4 shows a side view of a detail of Fig. 3, and Fig. 5 illustrates a side view of a 30 modified detail.

In these drawings 1 denotes the main uprights of the machine frame, which are connected by cross-members 2. The embroidery-frame 3 rests by means of rolltrs 4 on 35 horizontally disposed rails 5, which in turn are vertically displaceable in guide-supports 6.

In the construction, illustrated in Figs. 1 and 2, horses 7 for journaling pulleys are 40 provided on the main uprights 1, and flexible draft-members, such as ropes, flat metal bands or the like, run over these pulleys and are respectively secured to the horizontal rails 5 and to the drums 10, which latter are 45 fixed on the shaft 11. This shaft extends clear across the machine and is journaled in brackets 12 on the uprights 1 and in bearings 13 on the upper cross member 2. To the shaft 11 is secured near one of the brackets 12 a curve or cam 14 to which in turn is secured the upper end of a draft-member 15. Its lower end is secured to the cam 16 which is fixed on the shaft 19. The latter is journaled in bearings 17 and 18 which are 50 respectively secured to the machine upright and to the lower cross-member. To the cam

16 is secured the one end of the torsional spring 20, wound around the shaft 19 and whose other end is secured to a worm wheel 21. This latter rides loosely on the shaft 60 19 and meshes with an incased worm, as at 22, which may be operated by rotating its square-ended shaft 23 (Fig. 1).

The two cams, interconnected by the flexible member 15, together with the helical 65 spring 20 form the counterbalancing device for the embroidery-frame, inasmuch as on displacement of the frame the lever arms of the cams vary, in keeping with the increase or decrease of the tension of the 70 spring 20, in such manner that the compensation of the forces for all positions of the work-frame is assured.

By transmitting the movement to the work-frame by means of the shaft 11, the 75 frame, no matter how wide, is so supported that its up and down movements will ensue absolutely evenly.

In the modified form of construction, shown in Figs. 3 and 4, there is secured near 80 each end of the shaft 11 a cam 14, each of which is connected to a corresponding lower cam 16. Correspondingly there are provided two shafts 19, two torsional springs 20 and two worm gears. Between the uprights 1 85 there are secured to the cross-members 2 brackets 24 in which are provided bearings 25 for the shaft 11, bearings 26 for pulleys 8, and supports 6 for the horizontal guide-rails 5. Flexible draft-members 9 are secured respectively to the guide-rails 5 and to the drums 10' fixed on shaft 11, and run over the pulleys 8, as clearly shown in Fig. 4. In this construction, then, the counterbalancing device comprises two pairs of cams, 95 the two cams of each set being interconnected by a flexible member and influenced by a torsional spring, and deformation of the work-frame by sagging is effectively prevented for the reason that the frame is suspended from a plurality of intermediate 100 flexible members, one near each bracket 24.

Instead of using a single long shaft 11, it is obvious that also several short shafts may be used, in which instance the several 105 shafts 19 would have to be united into a single shaft extending clear across the machine.

The torsional spring 20 can also be replaced by a draw-spring 27, as shown in 110 Fig. 5, whose one end is suitably secured to the machine frame, and whose other end is

secured to a disk or drum 29 by means of the interposed flexible member 28.

By connecting counterbalancing device and work-frame by a shaft and flexible draft-members, the device can be so mounted on the machine that the operating height and width of the latter is in no wise interfered with, with the result that the space available for setting-up the machine can be 10 utilized to the fullest extent.

What I claim is:

1. The combination with the supporting frame of an embroidering machine and the work frame thereof; of shafts mounted on 15 the supporting frame, pulleys mounted on the supporting frame, drums on one of the shafts, flexible connections from said drums and passing over said pulleys to the work frame, oppositely directed cams on the 20 shafts, flexible members connecting the cams and adjustable counterbalancing mechanism coöperating with said cams.

2. In an embroidering machine, the combination with the machine frame and the 25 work frame thereof; of drums and guide pulleys mounted on the machine frame, flexible suspending means guided by said pulleys and connecting the drums and work frame; oppositely directed cams having a 30 flexible connection between them, and counterbalancing means for the work frame comprising resilient means acting on one of the cams and means for altering the tension on 35 said resilient means.

3. In an embroidering machine, the combination with the machine frame and the work frame thereof; of drums and guide pulleys mounted on the machine frame,

flexible suspending means guided by said pulleys and connecting the drums and work frame, oppositely directed cams connected with the drums, flexible connections between the cams, suspending means connected to the frame at points intermediate its ends, and counterbalancing means for said work frame 45 operating through said cams and aforesaid suspending means.

4. In an embroidering machine, the combination with the work frame thereof; of a plurality of flexible suspending members 50 connected to the frame, and a like number of drums to which said members are connected and on which they are adapted to be bound to raise and lower the frame, a counterbalancing spring for said work frame 55 connected to the drums, connections between the drums and means for altering the tension of the spring.

5. In an embroidering machine, the combination with the work frame thereof; of a 60 counterbalancing suspension for the frame, comprising an upper and a lower shaft, a drum on one shaft, adjustable spring tension means on the other shaft, a flexible suspending member connected at one end to the drum and at the other end to the frame, two 65 oppositely directed cams, one of which is mounted on each shaft and a flexible connecting member connected at opposite ends to said cams.

In testimony whereof I have affixed my signature in presence of two witnesses.

WILHELM ALBERT STELLMACHER.
